Primary Examiner—Celia Murphy

[57] **CLAIM**

The ornamental design for a beach poncho, as shown and described.

DESCRIPTION

FIG. 1 is a front elevational view of a beach poncho of conventional thickness showing my new design;

FIG. 2 is a rear elevational view thereof; and,

FIG. 3 is a front elevational view thereof shown in use, the broken lines partially showing a human figure being for illustrative purposes only and forming no part of the claimed design.
